VENEER CLAMP

Anthony Calabro, Brooklyn, N. Y., assignor of
one-third to Joseph Adamo, Brooklyn, N. Y.

Application July 19, 1948, Serial No. 39,441

2 Claims. (Cl. 144—281)

1

The present invention relates to clamps and presses which are especially, but not necessarily, adapted for satisfactorily applying and fastening a strip of veneer to a complementary work-piece.

More specifically, the invention has to do with a portable clamp or press for veneering pieces of furniture, desks and table tops and the like. It is the practice in many shops to utilize comparatively large heavy duty veneering presses and, ordinarily, it is necessary to take the work to the press. The principal object of the present invention is to provide a portable or hand-type veneering press in the form of a clamp and to utilize any number of clamps needed to obtain the desired ends, whereby the user takes the clamping press to the site of the work instead of carting or otherwise taking the work, often unwieldy and burdensome structures, to the stationary press.

Needless to say, I am aware that portable clamps used as veneering presses are not new. Therefore, in presenting the instant matter, I seek to cover and protect the specific structural improvements and refinements which are embodied in the press and not the procedure or method followed in utilizing said press.

One version of the invention, structurally speaking, has to do with the adoption and use of a horizontal base unit having studs secured in the end portions thereof and rising at right angles therefrom, said studs serving to assemble and adjustably maintain in place a complementary relatively movable clamping unit, coiled springs being employed and surrounding the studs and interposed between the end portions of the two units for cushioning the relatively movable unit and for lifting it on the studs to automatically spread the two units apart for expeditious handling and use.

Another object of the invention is to provide a structure of the stated type characterized by said base and clamping units, the latter unit being provided with elongated slots and complementary keyways to accommodate longitudinally adjustable hand turned pressure screws, said pressure screws serving to apply pressure to a coacting pressure equalizing member which rests on the veneer for purposes of firmly and evenly spreading and holding same while it is glued to the complementary foundation or work-piece.

Another object of the invention is to provide complementary clamping units wherein each unit is made up of sections which have block-like central inserts and connecting plates whereby the inserts and sections may be collectively extend-

2

ed or contracted for purposes of varying lengths of the respective units whenever necessary or desired.

Other and more specific features and advantages will become more readily apparent from the following description and the accompanying illustrative drawings.

In the drawings, wherein like numerals are employed to designate like parts throughout the views:

Figure 1 is a perspective view showing a fragmentary portion of a work bench or table, and showing the clamping press constructed in accordance with this invention and illustrating the manner in which same may be conveniently used for veneering work,

Figure 2 is a side elevational view of the veneering press or clamp constructed in accordance with my ideas and separate from the work bench and the work,

Figure 3 is a bottom plan view of the structure seen in Figure 2,

Figure 4 is a top plan view of the structure seen in Figure 2,

Figures 5 and 6 are cross sections on the lines 5—5 and 6—6 respectively of Figure 4,

Figure 7 is a perspective view of one of the hand regulated pressure screws,

Figure 8 is a fragmentary perspective view, on an enlarged scale with the essential parts "exploded" but in proper relative positions of one of the units,

Figure 9 is a longitudinal section on an enlarged scale, taken on the line 9—9 in Figure 4, looking in the direction of the arrows, and,

Figure 10 is a detail view showing a modified type of insert carrying a pressure screw.

Referring now to the drawings by distinguishing reference numerals attention comes first to Figure 1 wherein 12 denotes a suitable work bench or table with appropriate supporting legs 13. The work-piece or foundation part of the work, broadly speaking, is denoted by the numeral 14 and is a piece of wood which may be of any size and proportions. The strip of veneering which is to be applied thereto and glued is denoted by the numeral 15. On the other hand the numeral 16 designates a pressure piece which is adapted to receive the thrust from pressure screws to uniformly apply the pressure to the veneering to spread it and to compress it and hold it flat against the foundation until it adheres, by intervening glue or other adhesive, thereto.

In the drawings the bottom or base unit of the press is denoted, as a general assemblage, by the

numeral 17 and the complementary relatively movable top or clamping unit is denoted by the numeral 18. These two units are of equal lengths and disposed in spaced parallelism and the base unit is adapted to extend crosswise of the table top 12 as shown while the other unit 18 is above the table and is adapted to be brought down to apply the wanted pressure. In many instances these units 17 and 18 could be of one-piece construction but experience has shown that it is generally necessary to make said units of sections which may be shortened or lengthened by proper adjustment to accommodate work pieces of varying lengths and to insure the application of uniform pressure. The base unit 17 (see Figure 2 and 3 in particular) is made up of companion substantially duplicate sections 19 and 20 the inner ends of which are notched or stepped to provide extensions 21 which have half-lap jointing connection with similar shoulder extensions 22 on the ends of an insertable and removable filler block 23. The opposite longitudinal side faces of the parts 19, 20 and 23 are provided with channels or grooves 24 (see Figure 6) which accommodate insertable and removable metal connecting braces 25 having elongated slots 26 to accommodate and permit passage of the end portions of assembling and retaining bolts 27, the latter held in place by thumb nuts 28 bearing against suitable coacting washers 29. The end sections 19 and 20 are provided with rigid right angularly disposed assembling studs 30 having pin holes 31 and longitudinally spaced points to accommodate an insertable and removable L-shaped pin or key 32 which serves in a manner to be hereinafter described. Reference being had first to Figure 5, it will be seen I provide rectangular plates held in place by screws, said plates being denoted by the numeral 33 and said plates having sockets 34 to accommodate the screw-threaded end portions 35 of the rods or studs 30. Thus, the unit 17 is made up of duplicate sections 20 carrying right angularly disposed attachable and detachable studs 30 and an intervening filler block 23 and connecting slotted plates 25 and bolts 27, as shown.

The complementary clamping unit 18 is made up along similar constructional lines. That is to say, said unit 18 is characterized by outer duplicate sections 36 and 37 having transverse holes for passage of the studs 30. Coiled springs 38 are provided and are interposed between the respective sections 19, 20, 36 and 37 and the springs serve to "float" the entire unit 18 and also to cushion it and to assist in releasing it from clamping position when the pins 32 are removed. Referring to Figure 8 at this stage, it will be seen that the inner end portions of the sections 36 and 37 are notched to provide shoulders 39 which engage coacting properly arranged shoulders 40 on the end portions of the insertable and removable block or insert 41. So, here again we have the inner ends of the main sections having half-lap jointing connection with the interposed filler block, the same as described in connection with the unit 17. The filler block 41 has grooves in opposite sides denoted at 42 which register with similar grooves 43 in the end sections to accommodate coacting portions of the connecting plate 44. The plate has elongated slots 45 to accommodate projecting assembling and retaining studs or bolts 46 and 47. Here again the bolts are provided with washers 48 and thumb nuts 49. It follows that the sections 36 and 37 may be slid toward and from each other between the

assembling plates 44 making it possible to insert blocks of different sizes. That is to say, I might use a relatively short block instead of the one 41 shown and the blocks will vary in lengths depending on the degree of adjustment required in changing the overall length of the unit 18. Incidentally, it may be pointed out that some of the inserts may be sufficiently long that they would have to have stabilizing studs 47 and some may be short as shown for example in Figure 1 wherein no such studs are required.

It will be noted that the sections 36 and 37 are provided with elongated slots 50 to accommodate hand positioned and regulated pressure screws 51. These pressure screws are threaded through nuts 52 as shown in Figure 7. The nuts are slid back and forth in keyways 53 provided in inner opposed surface of the walls, that is, the longitudinal walls of said slots 50. Consequently, the pressure screws may be slid toward and from each other depending on the length of the pressure applicator piece or member 16 as shown in Figure 1. In case it is necessary to put a large filler block between the sections, say the sections 36 and 37, for instance the long block such as shown in Figure 10 at 54, suitable shoulders will be provided at 55 and an extra thrust screw (maybe two if necessary) 56 will be provided. This will be threaded through an adapter 57 which is screwed in place at 58 and said screw will have swivelly mounted work head 59. Incidentally, the aforementioned pressure screws 51 (see Figure 7) also have swivelly mounted self-leveling pressure heads 60.

In reviewing the structure it will be seen that the base or lower unit of the complete press is denoted by the numeral 17 and is characterized by longitudinally extensible and contractable components 19 and 20 with interposed central filler means and connecting plates. The upper section 18 is of a corresponding construction and may be extended and contracted so that both units 17 and 18 may be used in proper united and companion relationship. They are held in respective positions by the studs 30 and fastening pins 32 and cushioning springs 38 are provided for the stated results. It follows that the upper and lower units may be adjusted to desired lengths for the particular job required. Then, the structure is located on the work bench or elsewhere to accomplish the desired job. By interposing the pressure equalizer 16 between the sheet of veneer and the upper unit 18 and then adjusting the pressure clamps 51 in the slots 50 they may be arranged at the most advantageous positions to uniformly "spread" the pressure which is applied distributively to the veneer. The upper unit 18 is slid down on the studs 30 against the tension of the expansion springs 38 to an approximate working position. Then, the final and finer adjustment is made by bringing the thrust or pressure screws into contact with the part 16 and the work made up of parts 14 and 15. It will be seen therefore that the range of utility, complementary relationship and adjustment of various parts is such as to permit the invention to serve satisfactorily. It is to be pointed out that it may be necessary to make the sections 36 and 37 in complementary parts, an upper part for example and a lower part 61 which is screwed or otherwise held in place as shown in Figure 9. This is to facilitate the assembling and removal of the nuts 52 in relation to the slide ways or key ways 53, as is obvious.

It is reasonable to believe that persons familiar with the construction and use of wood working and equivalent clamps and portable presses will clearly understand the invention, the mode of constructing the essential sections and units of same and the manner in which said units are assembled and used, adjusted, repaired and the like.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention, what is claimed as new is:

1. As an article of manufacture and as a component part of a veneer press of the class described, a pair of duplicate end sections having shoulder portions at their inner adjacent ends, a filler block interposed between said inner ends and having shoulder portions, the respective shoulder portions on the filler block and inner ends of said sections being in overlapping relationship, the side walls of said sections and block having aligned grooves, plates fitted in said grooves, said plates having elongated slots, said filler block and sections having nut equipped bolts operable through said slots, said end sections having assembling studs arranged to extend at right angles to the sections.

2. As a new article of manufacture and as a

component part of a veneer press of the class described, a clamping unit made up of duplicate end sections and an intervening insertable and removable filler block constituting a center section, the coacting ends of the filler block and the said sections being inter-connected in half-lap relationship, side plates bridging the interconnected end portions of the sections and filler block, said plates having slots, studs mounted in said sections and extending through said slots and serving to hold the block end sections in assembled but separable relationship, said end sections having elongated slots provided with key-ways, key forming nuts slidable in said key ways, and pressure screws threaded through said nuts and located for adjustment in said slots.
